UNITED STATES PATENT OFFICE.

WILLIAM T. DRYDEN, OF ARGENTA, ARKANSAS.

FARE-BOX.

SPECIFICATION forming part of Letters Patent No. 364,164, dated May 31, 1887.

Application filed July 29, 1886. Serial No. 209,435. (No model.)

To all whom it may concern:

Be it known that I, WILLIAM T. DRYDEN, a citizen of the United States, residing at Argenta, in the county of Pulaski and State of 5 Arkansas, have invented a new and useful Improvement in Fare-Boxes, of which the following is a specification.

My invention relates to shelf-operating mechanism for fare-boxes, and will be fully 10 described with reference to the accompanying drawings, and more particularly pointed out in the claims.

Figure I represents in side elevation my improved shelf-operating mechanism, the levers 15 being in position of rest and the covering-plate being removed. Fig. II is a similar view showing both levers partly raised. Fig. III is a similar view showing the lower lever raised to its full extent and the upper one returned 20 temporarily to horizontal position. Fig. IV is a rear elevation of the box.

1 1 represent the sides or frame of a fare-box, 2 the fare-receiving shelves, and 3 the levers, preferably rigid therewith, for operating the same. An additional plate or block, 4, is applied to one side of the box to protect the levers, slots being provided, through which the front ends of said levers project to permit the operation of the same by hand. The 25 shelves, and consequently the levers to which they are attached, are arrested by stops 5. (Shown in dotted lines in Fig. I.)

It will be readily seen that by raising the outer ends of the levers the shelves are tipped 30 and any fares resting thereon discharged. When the upper lever is lifted, the shelf alone to which it is attached is tilted. To enable the operation of the two shelves together, however, on the lifting of the lower lever, I 35 pivot to said lower lever a curved rod, 6, which projects between studs 7, fixed to the side 1

of the box and rests loosely under the upper lever. The end of the rod 6 bearing against the upper lever may be enlarged transversely of said lever, so as to insure its engagement therewith. When the lower lever is lifted, it tilts the shelf connected therewith, and at the same time lifting the upper lever will tilt the upper shelf. The lower lever continuing its motion will then force the curved rod to the rear of 50 the upper lever, allowing the latter to fall. When then the lower lever is released, it falls by its own gravity, and the rod 6, falling back to position again, rapidly tilts the upper shelf, insuring the discharge of any fares resting 55 thereon. The three positions of the lever are shown in Figs. I, II, and III.

Having thus described my invention, the following is what I claim as new therein and desire to secure by Letters Patent:

1. In a fare-box, in combination with shelves and their operating-levers, a rod carried by the lower lever, curved substantially as shown, and guided in contact with the upper lever, as and for the purpose set forth. 60

2. In combination with shelves and bent operating-levers therefor, a rod connected to a lower lever and bearing normally under the upper lever in such manner as to pass behind the elbow on said upper lever when the lower 7c one is raised to its extreme position, substantially as shown and described.

3. A fare-box, in combination with shelves and operating-levers therefor, and a rod pivoted to a lower lever, bearing under said upper 75 lever, and having guides fixed to the fare-box, enabling it to operate said upper lever, substantially as described.

WILLIAM T. DRYDEN.
